CLAIM

The ornamental design for a floating poker table, as shown and described.

DESCRIPTION

The claimed floating poker is used to play a multitude of card games on in a pool or other body of water.

FIG. 1 is a top plan view of a floating poker table, showing our new design;

FIG. 2 is a front elevation view, the rear elevation being a mirror image

FIG. 3 is a right side elevation view, the left elevation being a mirror image; and,

FIG. 4 is a bottom plain view of the table.
